UNITED STATES PATENT OFFICE.

FRANK F. KOZAK AND GEORGE LUTZ, OF MILWAUKEE, WISCONSIN.

WINDOW LATCH.

Application filed September 2, 1926. Serial No. 133,222.

This invention relates to window latches.

Objects of this invention are to provide a simple type of window latch which may be applied to the window sashes in an inconspicuous manner, and which may be used without damage or abrasion of the sashes, and which nevertheless is effective in operation.

Further objects are to provide a novel form of window latch which will permit the use of the window in an ordinary manner and which will also allow the locking of the window in a partially opened condition for ventilation, for instance, and will prevent further opening of the window.

An embodiment of the invention is shown in the accompanying drawings in which:

Figure 1 is a face view of the device showing it applied to the window and showing a fragment of the window;

Figure 2 is a sectional view transversely through the window;

Figure 3 is a sectional view on the line 3—3 of Figure 1.

Referring to the drawings, it will be seen that the upper window pane is indicated by the reference character 1, and the lower window pane by the reference character 2. These window panes are carried in an upper sash 3 and a lower sash 4. The upper sash is provided with a plate 5 secured thereto by means of screws 6 which are counter sunk in the plate 5, as shown in Figure 2, and it is to be noted that the lower end of the plate is provided with an enlarged portion 7. This portion 7 forms, in reality, a pair of ears, between which a movable tongue 8 is pivotally carried by means of a pintle pin 9. Preferably, the tongue is slightly narrower than the space between the ears and is pressed in one direction by means of a spring 10 which loosely surrounds the pintle pin. This tongue is provided with a latching shoulder which fits a corresponding recess 11 formed in one of the ears 7, as shown in Figures 1 and 3, to thus latch the tongue against inadvertent motion. Preferably, also the tongue is provided with a rounded cut-away portion

12 for easy insertion of the finger when the tongue is turned into the dotted line position shown in Figure 2. When in this last mentioned position, the window sashes may be easily moved past each other, as the tongue will clear the upper end 13 of the

lower window sash. This upper portion 13 of the lower window sash is provided with a contact or bearing plate 14 held in place by means of a counter sunk screw 15. It is also provided with a prong 16 to prevent its turning out of place.

In using the device, the tongue 8 is rocked outwardly at right angles to the upper window sash, as shown in full lines in Figure 2, and when it is attempted to move either of the sashes, the tongue will contact with the bearing plate 14 and will arrest and prevent further motion of the sashes.

On the other hand, when it is desired to operate the windows in the usual manner, it is merely necessary to rock the tongue 8 into the dotted line position shown in Figure 2, where such tongue will pass freely by the lower sash without engagement. It will be seen, therefore, that a very simple and inconspicuous latch has been provided for a window which will permit the partial opening of the window, but will restrain the sashes against further motion.

Although the invention has been described in considerable detail, such description is intended as illustrative rather than limiting as the invention may be variously embodied and as the scope of such invention is to be determined as claimed.

We claim:

A latch for a pair of relatively movable window sashes, said latch comprising a bearing plate carried by one end of one of said sashes, a second plate carried by the face of the adjacent sash and secured thereto and having projecting ears, a tongue pivotally mounted between said ears and adapted to extend either outwardly at right angles to the second mentioned plate or in alignment therewith, said tongue being adapted to contact with the bearing plate when it projects outwardly with respect to said second mentioned plate, said tongue and said second mentioned plate having interengaging spring pressed retaining means for temporarily holding said tongue in its outwardly projecting position.

In testimony that we claim the foregoing we have hereunto set our hands at Milwaukee, in the county of Milwaukee and State of Wisconsin.

FRANK F. KOZAK.
GEORGE LUTZ.
